[57] CLAIM

The ornamental design for a table, as shown and described.

DESCRIPTION

FIG. 1 is a perspective view of a table showing my new design;

FIG. 2 is a top view thereof;

FIG. 3 is a bottom view thereof; and

FIG. 4 is a front elevational view.

The elevational views taken at 60° intervals around the table are identical to the front elevational view.

FIG. 1

FIG. 2

FIG. 3

FIG. 4
